(57) CLAIM

The ornamental design for the exercise equipment, as shown and described.

DESCRIPTION

FIG. 1 is a perspective view of exercise equipment showing my new design;

FIG. 2 is a rear view thereof;

FIG. 3 is a front view thereof;

FIG. 4 is a first side view thereof;

FIG. 5 is a second side view thereof;

FIG. 6 is a top plan view thereof; and,

FIG. 7 is a bottom plan view thereof.

Broken lines in the drawings are for showing portions of the exercise equipment and form no part of the claimed design.

1 Claim, 6 Drawing Sheets

FIG. 2FIG. 3

FIG. 4

FIG. 5

FIG. 6

FIG. 7
